UNITED STATES PATENT OFFICE.

ALBERT F. SAUNDERS, OF SYRACUSE, NEW YORK, ASSIGNOR TO T. N. BENEDICT MFG. CO., OF EAST SYRACUSE, NEW YORK.

DESIGN FOR A BORDER STRIP FOR A DISH OR SIMILAR ARTICLE.

Application filed January 31, 1928. Serial No. 25,089. Term of patent 3½ years.

To all whom it may concern:

Be it known that I, ALBERT F. SAUNDERS, a citizen of the United States, residing at 106 Rugby Road, city of Syracuse, county of Onondaga, and State of New York, have invented a new and original Design for a Border Strip for a Dish or Similar Article, of which the following is a specification, reference being had to the accompanying drawing, showing my new design.

Fig. 1 is shown broken off, but the ornamentation is the same as that shown at the upper part thereof.

Fig. 1 is a plan view of the border strip showing my new design.

Fig. 2 is an edge view of the border strip.

I claim:

The ornamental design for a border strip for a dish or similar article substantially as shown and described.

In testimony whereof, I have hereunto signed my name at East Syracuse, in the county of Onondaga and State of New York this 22nd day of March, 1928.

ALBERT F. SAUNDERS.
